UNITED STATES PATENT OFFICE.

EUTHADDEUS I. BROWN, OF PRINCESS ANNE, MARYLAND.

APPARATUS FOR PRINTING PHOTOGRAPHS.

No. 810,907.

Specification of Letters Patent.

Patented Jan. 30, 1906.

Application filed March 10, 1905. Serial No. 249,343.

To all whom it may concern:

Be it known that I, EUTHADDEUS I. BROWN, of Princess Anne, in the county of Somerset and State of Maryland, have invented certain 5 Improvements in Apparatus for Printing Photographs, of which the following is a specification.

In the description of the said invention which follows reference is made to the accompanying drawings, forming a part hereof, and in which—

Figure 1 is an exterior front view of the apparatus. Fig. 2 is a partly-sectional view of the lower part of Fig. 1, taken on the dotted line $\alpha\alpha$. Fig. 3 is a partly-sectional view of the motive mechanism shown in Fig. 2 looking in the direction indicated by the arrow in the figure. Fig. 4 is a perspective view, on a reduced scale, of the apparatus as it appears when in use.

Referring now to the drawings, 1 is a cabinet adapted to stand on a table in a dark room. The cabinet is provided with an electric or other lamp. (Not shown.) The front and 25 rear boards of the upper part α of the cabinet which overhang the lower part b are provided with apertures 2, which when uncovered admit of the passage of light from the lamp to the photograph-plates in frames 3, which 30 are arranged exteriorly of the cabinet, as hereinafter described. To support the frames 3, carrying the photograph-plates within the range of the light-rays from the lamp, the cabinet is provided with brackets 4, along 35 which the holders 6 for the frames are adapted to slide and be adjusted in distance with respect to the cabinet. The brackets, frames, and their holders are well shown in Fig. 4.

Referring now to Figs. 2 and 3, 5 is a clock-movement, the center wheel 7 of which rotates once in sixty minutes and has forty teeth, which wheel engages with the wheel 9, having twenty teeth, secured to the shaft 10. 12 12 are time-wheels placed loosely on the shaft 10 and driven from the said shaft, by means of loose spiral springs 13, the one to the left in Fig. 2 extending endwise between the hub of the time-wheel and the hub of the wheel 9. The said spring forces the time-wheel against 45 a collar 15, pinned to the shaft 10, thereby producing sufficient friction to effect the rotation of the time-wheel and the closing of a shutter, hereinafter described. The other time-wheel—that is to say, the one to the right 50 of Fig. 2—is driven in a similar manner except that its spiral spring bears against the col-

lar 16 next to the frame 17 of the clock-movement instead of the hub of the wheel 9. The rims of the time-wheels 12 are either notched or broken, as shown in Fig. 3, the notches or spaces being denoted by 19. The purpose of the said notches will be hereinafter described.

20 20 are shutters situated within the cabinet and secured to the ends of arms 22, fastened to the independent vibratory shafts 24. 65 The arms 22 pass through and are adapted to vibrate in suitable slots in the bottom of the overhanging or upper part α of the cabinet to cover or uncover the apertures 2 in the front and rear boards of the cabinet. The vibratory shafts 24 also carry the bent arms 25, the ends of which are adapted to enter the slots or spaces 19 in the time-wheels, and to enforce this action of the arms 25 and thereby instantly close the shutters the vibratory shafts 70 24 are connected to the front and rear boards of the cabinet by means of the coiled springs 27, which are under tension. The vibratory shaft is also provided with the straight arms 29, the extreme ends of which are bent at a 80 right angle and when in service rest on the wire cams 30 on the loose extension-shafts 32, which may be rotated independently of the shaft 10. The cams 30 in the rotation of the shaft 10 in the direction indicated by the dotted arrow in Fig. 3 and which direction is the reverse of that produced by the clock-movement elevate the straight arms 29 and cause the opening of the shutters, and in this operation the ends of the bent arms 25 are 85 lifted from the notches 19, and thereby admit of rotation of the time-wheels. The loose extension-shafts 32 are turned independently, as described, by hand through the mediums of crank-handles 34, and the means of con- 90 nection between the said extension-shafts and the time-wheels whereby the latter are rotated independently of the clock-movement consist of the fingers 35, fixed to the said shaft, and the arms 37, tight on the hubs of the time-wheels, the same engaging in the rotation of the extension-shafts. A finger and arm are 95 shown approaching engagement in Fig. 3.

39 39 are segmental indicators secured to the front and rear boards of the lower section b of the cabinet, through the hubs of which the extension-shafts 32 pass loosely, and they are provided with an inner and an outer row of holes, respectively, denoted by c and d , arranged in semicircular lines concentric with the said shafts, as shown particularly in Fig. 1. There are preferably fifteen holes in each

curved row, and the inner holes are placed between the outer ones, and as a complete rotation of a time-wheel when effected by the clock-movement is performed in thirty minutes either time-wheel may be set by means of the crank-handle in such a position that upon the release of the crank it will allow the drop of its bent arm and the closing of the shutter at the expiration of fifteen minutes or less. When the exposure of the light-rays to a photograph-plate is required to be less than fifteen minutes, the movement of the crank-handle to rotate the time-wheel is limited by placing a pin in one of the holes, which serves as a stop to the movement of the crank-handle, as hereinafter more particularly described.

By reference to Fig. 3 of the drawings it will be seen that the shape of the wire cams 30 is such that it requires only a slight rotation of the crank-handles to open the shutters and that the bent arms 25 are lifted out of the slots or spaces 19 before the time-wheels are made to rotate by the engagement of the fingers 35 with the arms 37.

43 48 are plates of orange-colored glass to enable the operator to fill plate-frames at one side of the apparatus and develop pictures at the other.

30 The operation of the apparatus is as follows: Supposing that in printing a plate has to be exposed to the light for twelve minutes, the printing-frame 3 is placed on a holder 6, which is slid longitudinally of its bracket 4 until it reaches a position where it will be subjected to the proper intensity of light. A pin (shown in Figs. 1 and 4 and denoted by 41) is then placed in the twelfth hole from the top on the outer curved row of holes in the segmental indicator and the crank-handle 34 turned in the direction indicated by the arrow in Fig. 1 until it is stopped by the said pin, when it is released. From the foregoing description it will be understood that in the movement of the crank-handle just described the cam 30 has operated to open the shutter 20, the bent lever 25 has been lifted out of the notch 19 and clear of the rim of the time-wheel 12 and then dropped onto the said rim. The time-wheel also is carried to such a position that when it is rotated in a reverse direction by means of the clock-movement for the period of twelve minutes its edge 42 will pass from under the end of the bent lever 25 and the shutter 20 be instantly closed. It will be further understood that in the return rotation of the time-wheel 12 or that effected by the clock-movement, as described, the end of the arm 29 passes from the portion of the cam 30 which is concentric with the extension-shaft

32 to the part which is nearly radial, and thereby allows the end of the bent wire 25 to fall into the slot 19 when the time limit of exposure has been reached.

The apparatus as described admits of printing at either the front or the rear of the cabinet independently of the other and with different periods of exposure, while the intensity of the light may be regulated by the adjustment of the printing-frames toward and from the lamp. It also admits of manipulations of plates and pictures at the sides of the cabinet in a protected light which passes through the orange-colored glass plates.

I claim as my invention—

1. In an apparatus for printing photographs, an interiorly-lighted cabinet having openings in the walls thereof for the emission of light, and means to support in a stationary condition photograph-frames, adjustable in position with respect to the said openings, combined with shutters for the said openings, a clock-movement to operate the said shutters, and mechanism whereby the operation of the said clock-movement is regulated to effect the duration of the time of exposure of the said openings, substantially as specified.

2. In an apparatus for printing photographs, a cabinet containing a lamp, having openings in its walls for the emission of light from the lamp, shutters which are held yieldingly in a condition whereby the said openings in the walls of the cabinet are covered, a clock-movement adapted when the shutters are opened by hand, to cover the same, and mechanism whereby the time of exposure, is regulated, and means for supporting photograph-frames exteriorly of the cabinet, and adjustable with reference to the openings in the cabinet, substantially as specified.

3. In an apparatus for printing photographs, comprising an interiorly-illuminated cabinet with openings in the walls thereof, the combination of a shaft, an arm extending from the shaft, a shutter on the said arm arranged to pass from a position over the said opening to one whereby the said opening is uncovered, a spring mechanism to yieldingly hold the said shutter in a closed position, a clock-movement which is normally inoperative to effect any movement of the shutter, and mechanism whereby the shutter is manually opened, and automatically closed by the clock-movement independently of the hand, substantially as specified.

EUTHADDEUS I. BROWN.
